FUR-COVERED SHOE VAMP

George Naidor, Gouldsboro, Pa.

Application June 28, 1947, Serial No. 757,849

1 Claim. (Cl. 36—45)

1
My present invention relates generally to footwear and has particular reference to an improved vamp construction for slippers and the like.

It is a general object of the invention to provide a shoe in which the vamp presents an exterior surface composed of fur. This is desirable in slippers and other types of footwear for indoor use. The fur commonly employed, and intended to be employed in carrying out the present invention, is of the long-haired variety derived from the pelt of a rabbit or similar small animals.

In making articles of this character, it has heretofore been the practice to form the vamp of an integral piece of fur cut to the shape desired and assembled with the sole in conventional manner. Because of the odd shape which a shoe vamp embodies, however, it has usually been impossible to cut more than one or two vamp pieces from a single pelt. As a result, footwear of this character has been relatively expensive.

It is an object of the present invention to produce an article of footwear in which the vamp is the same, in appearance and feel, as that which is formed of a single piece of fur, which is in a number of respects of greater comfort and enhanced appearance, and which may be constructed in an unusually economical manner. These desirable results are achieved by a unique association of two separate pieces of fur specially shaped and assembled in a novel manner in co-operative relation to each other and to the other parts of the shoe.

The features of the invention are applicable to slippers and similar articles of footwear of varying styles. For this reason, it is to be understood that the particular construction hereinafter described is purely illustrative.

I achieve the foregoing objects and advantages, and such other objects and advantages as may hereinafter appear or be pointed out, in the manner illustratively exemplified in the accompanying drawings in which:

Figure 1 is a plan view of a pelt from which one of the pieces of the present improved construction is cut;

Figure 2 is a similar view of a second pelt from which another of the pieces of the present construction is cut;

Figure 3 is a perspective view of the initial assembly of elements entering into the construction of one illustrative article of footwear;

Figure 4 is a cross-sectional view taken substantially along the line 4—4 of Figure 3;

Figures 5 and 6 are perspective views of certain further steps in the manufacturing procedure;

2
Figure 7 is an enlarged cross-sectional view taken substantially along the line 7—7 of Figure 6;

Figure 8 is a perspective view of the finished article of footwear;

Figure 9 is an enlarged cross-sectional view taken substantially along the line 9—9 of Figure 8; and

Figure 10 is an enlarged cross-sectional view taken substantially along the line 10—10 of Figure 8.

The article of footwear herein chosen for illustration (Figure 8) is of the type which includes a vamp 19, a flat heel seat 20 devoid of upstanding quarter, a heel 21 merging with a sole portion 22, and a strap 23 extending rearwardly from the vamp to encircle the foot of the wearer.

In forming the vamp for this shoe or slipper, I first form a blank 24 (Figure 3) having the desired vamp shape, this blank being composed of any suitable soft and flexible sheet material, such as a woven or felted fabric or the like. This blank serves as a base for the vamp construction, and is preferably provided with the concave cutout 25 at the front. The side edges 26 diverge rearwardly along slightly convex lines, and the blank is provided with a transverse rear edge 27.

A piece of fur 28, of crescent shape, is then secured to the base 24 with the points of the crescent directed rearwardly. I have illustratively shown how this piece may be secured to the base 24 by the simple expedient of an arcuate line of stitching 29 arranged substantially along the longitudinal axis of the crescent. The crescent-shaped piece has a forward convex edge 30 and a rearward concave edge 31, and it is to be observed that the edge 31 is spaced forwardly from the rear edge 27 of the base 24. This crescent-shaped piece of fur is of such size and is so located on the base 24 that the fur hairs will conceal the forward and side edge portions of the base 24 when the shoe is assembled.

Another step in the preliminary association of parts lies in securing a second piece of fur 32, in the form of an elongated strip, preferably substantially rectangular, to the rear edge 27 of the base 24. This is preferably achieved in the manner shown most clearly in Figure 4. The fur side of one longitudinal edge 33 of the strip 32 is stitched or otherwise secured to the underside of the transverse rear edge 27 of the base 24. I have illustratively shown the employment of a line of stitching 34.

During this preliminary assembly of the parts, the ends of the strap 23 may be conveniently en-

gaged by the stitches 34, as indicated most clearly in Figure 3. It is not essential, however, that the shoe embody a strap of this character, as will readily be understood by those skilled in the art.

This preliminary assembly may then be associated with a sole in any convenient or well-known manner. In the shoe illustrated herein, for illustrative purposes, the side edges 26 of the base 24 are stitched down, as at 35 (Figure 5), to an insole member 36. During this procedure, a plat-form-covering strip of fabric 37 may be engaged by the stitches 35, in the manner shown, so that by turning this strip 37 down and around the margin of the insole 36, as indicated in Figure 6, an attractive marginal edge is imparted to the shoe in the sole region. The shoe may then be completed by securing a heel to the rear portion of the insole 36, and finally adhesively applying an outer sole 38. The heel seat portion of the insole 36, as well as the heel itself, may be covered with suitable fabric or other material prior to the application of the outer sole 38.

It will be observed that the fur strip 32, in the finished construction, extends forwardly to overlie the rear part of the vamp base 24. The upward arching of the rear edge of the vamp may in itself be sufficient to hold this strip in position, but glue or other adhesive may be used to secure the skin side of the strip 32, in its central region, to the rear part of the base 4; i. e., the part which is uncovered by the crescent-shaped fur piece 28.

It will also be observed that the strip 32 is of such pre-selected width that its fur hairs merge throughout its transverse extent with the hairs projecting from the crescent-shaped piece 28. As a result, the finished vamp presents the appearance of a single piece of fur, no line of demarcation between the two fur pieces being discernible. Moreover, the rear transverse edge of the vamp presents a fur exterior which improves the appearance and adds to the comfort of the wearer.

It will also be noted that the fur hairs of the crescent-shaped piece, at the front of the shoe, conceal the existence of the toe opening formed by the cut-out 25. This is a desirable result achievable by the present improved assembly of parts, since the toe opening adds to the comfort of the wearer while its presence in a slipper-like article is not usually desirable for style purposes.

The comfort of the wearer is further enhanced by the fact that the under or inside surface of the vamp is composed of the relatively soft material of the base 24.

Of primary importance is the economy which I am enabled to effect, so far as the fur pieces are concerned. In this connection, attention is now directed to Figures 1 and 2. In Figure 1 a pelt 39 is indicated, and the spaced parallel transverse lines 40 indicate the lines along which this pelt may be cut to provide a multiplicity of elongated strips such as that designated at 32 in the other figures. Needless to say, each of the strips may be subsequently cut to any suitable or desired length. It will be noted that as many as eleven such strips may be formed from a single pelt. It

is to be understood, however, that these strips are not necessarily provided with accurately straight longitudinal edges, as shown, but that other shapes may be employed, if desired, without altering the basically elongated nature of these strips.

In Figure 2 I have indicated a similar pelt 41 from which a multiplicity of crescent-shaped pieces (such as that shown at 28 in the other figures), may be cut. A longitudinal line 42 indicates the line along which the pelt may be longitudinally cut to form two halves; and each half may then be cut along arcuate lines 43, and along marginal longitudinal lines 44, to form a series of crescent-shaped pieces. As indicated, as many as fourteen such pieces may be cut from a single pelt.

The important thing to observe is that the concave and convex edges of each crescent-shaped piece (i. e., the edges 30 and 31 of the crescent-shaped piece 28 shown in Figure 3) have the same radius of curvature. It is this contour which permits the piece 28, for example, to constitute one of a nested series such as those shown in Figure 2.

In general, it will be understood that those skilled in the art may in a number of respects modify the details herein described and illustrated without necessarily departing from the spirit and scope of the invention as expressed in the appended claim.

Having thus described my invention and illustrated its use, what I claim as new and desire to secure by Letters Patent is:

A fur-covered shoe vamp comprising a base of vamp shape having a transverse rear edge, a crescent-shaped piece of fur secured to said base with its concave edge facing rearwardly and spaced appreciably forwardly of said transverse rear edge, the fur hairs concealing the front and side edges of said base, and a complementary substantially straight strip of fur having the fur side of one longitudinal edge secured to the underside of said transverse rear edge substantially throughout the length thereof, said strip extending forwardly to overlap at least the pointed end regions of said crescent-shaped piece and to overlie the rear part of said base, the fur hairs of said fur piece and fur strip merging with each other transversely across the vamp.

GEORGE NAIDOR.
